HERBERT E. RIDER, OF NEW YORK, N. Y., ASSIGNOR TO EDWARD L. HALL, OF NEW YORK, N. Y.

TEMPERATURE INDICATOR

Application filed April 23, 1927. Serial No. 185,964.

My invention relates to thermostatically operated heat indicators, and the object of my invention is to provide a heat indicator suitable for use in the oven of a domestic gas range or cook stove.

A further object is to provide a device for the purpose, that may be made as an independent article of manufacture and which can be attached to an oven door and detached therefrom instantly without the use of tools.

A further object is to provide an indicator of this type that can be made at a very low cost and at the same time is sensitive to changes in temperature in the oven.

Referring to the drawings which form a part of this specification:

Figure 1 is a vertical sectional view thru an indicator embodying my invention, shown mounted on an oven door.

Figure 2 is a front view of the indicator.

Figure 3 is a back view, showing the spring clamp heat conductor partly broken away to show the back of the casing for the mechanism.

Figure 4 is a plan view of the device.

Figure 5 is a perspective view of the indicator hand.

A and A¹, indicate the oven and oven door respectively. B indicates a heat conducting clamp, one side of which also serves as a back for the casing C. The device is made about the size as shown in the drawings. The clamp comprises the portion B which rests within the oven, the top B¹, and the portion

B², all made integral from a sheet of heat conducting material such as copper or aluminum which has a high heat conducting capacity relative to iron.

The clamp is separated from contact with the oven wall except at its bottom end B³, and at the contact points B⁵; and with the oven door by the edge B⁴, and the points B⁶, which are provided by crimping the metal as illustrated, the purpose of which is to prevent conduction of heat from the clamp to the outer wall of the oven or door, thus permitting the heat to be conducted directly at oven temperature to the thermostat D which is mounted at D¹ on the conductor clamp portion B² near the upper end thereof so that the

heat will travel but a short distance to operate the thermostat and the conductor will not drop much in temperature due to radiation of the heat from the surfaces exposed to the outer atmosphere.

The casing C, is secured to the portion B² by clips E—E etc. made integral with the casing C, and which extend thru slits E¹—E¹ etc. formed in the said portion.

The upper end of the thermostat is held to the wall B² by a clip E², formed from a portion of the wall which is slotted on three sides and bent outward into the space F, and is formed with smaller clips G—G which are bent around the end of the thermostat as illustrated. The casing C, is cut away to provide an opening C¹ to expose to view a dial plate H which is graduated or otherwise imprinted to indicate the temperature readings.

The dial plate is made of any suitable material such as a thin sheet metal or card board, and is secured to the casing C by a pivot I.

A pin J, is secured to the casing C and extends thru and supports an indicator hand J¹ which swings on said pin J as the free end of the thermostat D, which extends thru the slot J², moves as the temperature in the oven fluctuates. The pointer J³ swings over the dial as illustrated. I prefer to cover the dial with a sheet of transparent material K, which is clamped by the pin J to the inner front wall of the casing substantially as shown.

The clamp is made wide to insure heat carrying capacity and to afford a strong spring pressure to hold it firmly to the oven door.

The crimped formation of the contacts B⁵ and B⁶ serve to stiffen this spring action.

The construction as a whole is simple and durable and may be made at a very low cost.

Having thus described my invention I claim as new:

1. A temperature indicator of the character described comprising a casing the back wall having an extension bent to form a hook to support the casing, said hook having embossed portions at the bight of the hook to 100

present contact regions of relatively small areas for the purposes set forth.

2. A temperature indicator of the character described adapted to be mounted on a support, comprising a casing having a temperature responsive element mounted therein on one wall thereof, said wall comprising a heat conductor in direct contact with one end of said element to conduct heat thereto and having a hook-shaped portion the bight of which is crimped to provide regions of relatively small areas of contact with the support.

In testimony whereof I have affixed my signature.

HERBERT E. RIDER.
